US00D798868S

(12) **United States Design Patent** (10) **Patent No.:** **US D798,868 S**
Daniel (45) **Date of Patent:** **** Oct. 3, 2017**

(54) **COMBINED SUBSCRIBER IDENTIFICATION MODULE AND STORAGE CARD**(71) Applicant: **Isaac S. Daniel**, Miramar, FL (US)(72) Inventor: **Isaac S. Daniel**, Miramar, FL (US)(**) Term: **15 Years**(21) Appl. No.: **29/574,636**(22) Filed: **Aug. 17, 2016****Related U.S. Application Data**

(63) Continuation-in-part of application No. 29/536,865, filed on Aug. 20, 2015, now Pat. No. Des. 773,466, (Continued)

(51) **LOC (10) Cl.** **14-02**(52) **U.S. Cl.**USPC ..... **D14/436**(58) **Field of Classification Search**

CLAIM

The ornamental design for a combined subscriber identification module and storage card, as shown and described.

DESCRIPTION

FIG. 1 is a front perspective view of the combined subscriber identification module and storage card;
 FIG. 2 is a rear perspective view thereof;
 FIG. 3 is a front view thereof;
 FIG. 4 is a rear view thereof;
 FIG. 5 is a right side view thereof;
 FIG. 6 is a left side view thereof;
 FIG. 7 is a top view thereof; and,
 FIG. 8 is a bottom view thereof.

1 Claim, 6 Drawing Sheets**Related U.S. Application Data**

and a continuation-in-part of application No. 29/570, 673, filed on Jul. 11, 2016, now abandoned.
